UNITED STATES PATENT OFFICE.

WILLIAM H. STROUSE, OF OSKALOOSA, IOWA, ASSIGNOR TO AMERICAN AUTOMATIC STOKER COMPANY, A CORPORATION OF ARIZONA TERRITORY..

MECHANICAL STOKER.

No. 918,482.

Specification of Letters Patent.

Patented April 13, 1909.

Original application filed February 3, 1908, Serial No. 414,087. Divided and this application filed July 23, 1908.
Serial No. 445,003.

To all whom it may concern:

Be it known that I, WILLIAM H. STROUSE, a citizen of the United States, residing at Oskaloosa, in the county of Mahaska and 5 State of Iowa, have invented certain new and useful Improvements in Mechanical Stokers; and I do hereby declare the following to be a full, clear, and exact description of the same, 10 reference being had to the accompanying drawings, forming a part of this specification, and to the letters of reference marked thereon.

This invention relates to improvements in 15 plungers adapted for use in that type of mechanical stokers illustrated in Letters-Patent heretofore granted to me, Nos. 840,722 and 840,723, dated January 8, 1907, the present application being a division of my application, Serial No. 414,087, filed Feb. 3, 1908.

20 The object of the invention is to provide a form of plunger which will more effectually distribute the fuel in the fire-box when operated or reciprocated back and forth in a right line.

25 The invention consists in certain novel details of construction and combinations and arrangements of parts, all as will be herein-after described and pointed out particularly in the appended claims.

30 Referring to the accompanying drawings: Figure 1 is a perspective view of the nose or forward end of the plunger, a portion of the body of the plunger being indicated in dotted lines. Fig. 2 is a top plan view, and Fig. 3 is 35 a side elevation of the nose or fuel distributing end of the plunger.

Like letters of reference in the several views indicate the same parts.

The plunger of the present invention at its 40 forward end is provided with fuel supporting ledges or flanged portions A, and from these ledges or flanged portions the surface at each side of the center projection B curves upwardly and inwardly with a curve of gradually decreasing radius, thereby forming 45 concave surfaces C, which will give the major forward impetus to the fuel which is to be distributed to the rear and side portions of the fire-box. In the present structure the 50 projecting surfaces C merge gradually into the fuel supporting flanges or ledges A, and into the central projection B, whereby the front of the said central projection B is made relatively broad, to cause a certain propor-

tion of the fuel to be projected directly in line 55 with the path of travel of the plunger, while the major portion of the fuel will be distributed laterally, and those portions of the fuel intended to be thrown to the sides of the fire-box will be given the greatest impetus, inasmuch as their path of free travel is the greater.

Immediately in rear of the surfaces C the nose piece is provided with side pockets D, 60 preferably having downwardly and outwardly inclined walls terminating near the bottom in a somewhat sharp outward curvature, whereby fuel held in said pockets and pushed into the fire-box will discharge on the inward stroke of the plunger at each side 65 of the nose, and will be thereby distributed to the sides and corners of the fire-box at each side of the door opening. In the preferred construction, these transverse pockets have their rear walls at the outer edges 70 curved forwardly to a slight extent, as at E, in order to retain the fuel on the forward stroke and to discharge the same after the nose piece has started on its backward movement. In other words, the outwardly 75 flaring forward walls E² of the pockets constitute the projecting or distributing faces, while the rear walls E', owing to their forward curvature, constitute retaining walls 80 against which the fuel will seat without 85 tendency to discharge during the rapid forward movement of the plunger.

Extending rearwardly from the transverse pockets are projections G, adapted for the reception of the forward end of a sheet-metal body portion, indicated at H in dotted lines. This construction permits of the production of the nose piece of the plunger in a single integral casting, well adapted to withstand wear and rough usage, and at the same 90 time permits of the firm attachment of the same to the forward end of a relatively light body portion which may be conveniently made of sheet metal and of an inverted trough formation so as to overlie and inclose the 95 power mechanism for reciprocating the plunger, as set forth in the before mentioned patents and application.

Having thus described the invention, what I claim as new, and desire to secure by Letters-Patent, is:

1. A head for a reciprocating plunger for mechanical stokers having a fuel projecting

- nose at its forward end provided with concave deflecting faces and transversely opening pockets in rear of said deflecting faces, whereby the fuel will be discharged from the 5 pockets transversely of the line of movement of the nose piece.
2. A head for a reciprocating plunger for mechanical stokers embodying a nose piece having concave deflecting faces and pockets 10 in rear of said deflecting faces having fuel retaining surfaces on their rear sides and fuel discharging surfaces on their forward sides, whereby the fuel will be discharged from the pockets during the rearward movement of 15 the plunger.
3. A head for a reciprocating plunger for mechanical stokers, having a fuel projecting nose at its forward end embodying concave deflecting faces, fuel supporting flanges projecting forwardly from the bottom of said deflecting faces and pockets having inclined walls located in rear of said deflecting faces and opening transversely at the sides of the 20 nose piece.
- 25 4. A head for a reciprocating plunger for mechanical stokers, having a fuel projecting nose at its forward end embodying fuel sup-

porting flanges, concave fuel deflecting surfaces at each side of the center line, and open-sided transversely arranged fuel pockets in 30 rear of said deflecting surfaces.

5. A head for a reciprocating fuel projecting plunger for mechanical stokers, embodying a nose piece having pockets therein open at the top and sides of the nose piece, and 35 having transversely inclined bottom walls, fuel retaining rear walls and fuel projecting forward walls, whereby the fuel will be discharged transversely during the rearward movement of the plunger. 40

6. A head for a reciprocating fuel projecting plunger embodying a nose piece having bottom forwardly extending fuel supporting flanges and concave fuel deflecting surfaces at each side of the center line, said deflecting 45 surfaces merging gradually into the supporting flanges at the bottom and merging gradually into and forming a relatively broad central projection between them, substantially as described.

WILLIAM H. STROUSE.
